UPHOLSTERY MACHINE

Jacob S. Kamborian, West Newton, Mass. (% International Shoe Machine Corp., 292 Main St., Cambridge 42, Mass.)

Filed Nov. 18, 1957, Ser. No. 697,220

10 Claims. (Cl. 1-2)

This invention relates to machines for stretching sheet material over one surface of a form, such as a rigid panel and securing the marginal portion on the back side of the form, such as disclosed in U.S. Patent No. 2,667,908, and according to the method disclosed in U.S. Patent No. 2,576,121, and the pending U.S. application Serial No. 623,497, filed November 20, 1956.

The objects of the invention are to provide an apparatus for covering relatively large panels and for applying flexible sheet material thereto, such as some of the plastics which are not readily amenable to the use of adhesive for attachment, to provide apparatus for pulling the margin over the edge with a greater uniformity than has heretofore been possible in spite of the somewhat stretchy character of the material and to provide apparatus for attaching the margin with fastening elements, such as staples without breaking through the margin. Another object is to provide apparatus for facilitating holding the panels and advancing the same during the attaching operation to facilitate stretching and pulling over both along the straight runs and around the corners without loss of control or wrinkling or bunching of the margin. Another object is to provide apparatus in which the pulling over can be applied without damage to the covering material or to a panel edge which is thin or soft. Another object is to provide apparatus for constantly taking up and compensating for slight losses in tension in the covering between the pulling over instrumentalities and the attaching means due to elasticity in the material so as to keep the material abreast of the panel at all times and to prevent biasing of the margin relative to the edge of the panel. Other objects are to provide an apparatus in which the operating instrumentalities are brought into operation automatically and in which there are adjustments which adapt it for use with covering materials and panels of different thickness.

As herein illustrated, the apparatus comprises instrumentalities for constantly operating on the marginal edge of a covering which has been applied to one side of a rigid backing, progressively to pull successive small areas of the margin heightwise with respect to the panel, a member at that side of the instrumentalities from which the margin is released after heightwise stressing which projects inwardly over the panel close to its surface and beneath which the margin as it is released from the instrumentalities is folded so as to lie flat against the panel, a staple driver next to the folding member arranged to drive staples into the laid down margin and means beyond the staple driver operating constantly on the margin to stress it in a direction to shift the margin in the direction of feed relative to the panel and at right angles thereto. The last-named means may be a slender roll arranged to turn about a horizontal axis parallel to the bottom of the panel and carries a helical rib for rubbing contact with the pulled over marginal edge. The roll is rotated in a direction to advance the marginal edge in the direction of feed at a faster rate than the panel is being advanced and is located

2

at a distance from the pulling over instrumentalities which is less than the distance between the driven staples. The pulling over instrumentalities are a pair of downwardly inclined rolls having tapering surfaces adapted to grip the marginal edge between them for stressing the latter heightwise and the folding means is arranged to be moved into and out of operative position overlying the surface of the panel as the rolls are moved into and out of the margin gripping position. A table situated beneath the instrumentalities holds the work engaged therewith, is movable vertically from an inoperative position to an operative position in time with the movement of the rolls into and out of position and in its operative position is yieldable so as to allow for irregularities in the thickness of the work. The staple driving mechanism is timed with respect to the feed, such that after a staple is driven and before the next staple is driven, the wiper which is operating at a comparatively high speed effects a forward shifting of the margin sufficiently to pull the margin between it and the pulling over instrumentalities taut for the insertion of the following staples. A roller situated in the table is turned in a direction to assist in advancing the work with reference to the operating instrumentalities. Preferably the roller is mounted for angular adjustment relative to the operating instrumentalities.

The invention will now be described in greater detail with reference to the accompanying drawings wherein:

Fig. 1 is a front elevation of the machine embodying the invention herein illustrated;

Fig. 2 is an isometric view of the upper part of the machine to larger scale with certain parts broken away and omitted, as seen from the right-hand forward corner of the machine;

Fig. 2a is a plan view of a portion of the work table showing a turned table support for the panel feed roll;

Fig. 2b is a section taken on the line 2b-2b of Fig. 2a;

Fig. 3 is a plan view looking down on the panel being fastened, showing the relative position of the instrumentalities operating on the marginal edge;

Fig. 4 is a vertical section taken on the line 4-4 of Fig. 3;

Fig. 5 is a vertical section taken substantially at right angles to that shown in Fig. 4, as seen from the right-hand side of the machine;

Fig. 6 is a vertical section taken at right angles to that shown in Fig. 4, as seen from the left-hand side of the machine;

Fig. 7 is a perspective view of the panel showing the association of the operating instrumentalities;

Fig. 7a is a detail of a microswitch in the control circuit;

Fig. 8 is a diagram of the pneumatic control system for the machine; and

Fig. 9 is a diagram of the electric control system for the machine.

Referring to Fig. 1, there is a base 10, shown in outline only, which mounts a platform 12 on which are supported the pulling over instrumentalities 14, the staple driver mechanism 16 and the wiper 18. The base 10 also mounts a vertically movable work supporting table 20 for yieldably holding the work in engagement with the operating instrumentalities.

The pulling over instrumentalities comprise a pair of downwardly tapering rolls 22 and 24, mounted on converging axes for rotation in opposite directions. The rolls are mounted in bearings carried by a supporting frame 26 which is tiltable relative to a horizontal plane so that the rolls may be disposed at a slight angle inclined downwardly and in the direction of feed, which angle may be adjusted to increase or decrease the stress applied to the margin. The bearing carrying the shaft of the roll 24, while tiltable with the frame 26, is fixed with

reference to its forward and rearward movement; whereas, the shaft of the roller 22 is mounted in bearings at the forward end of a slide 28, which is connected at its rear end to pressure operated means for moving the slide 28 forwardly, thereby to separate the rolls to facilitate introducing the marginal edge therebetween. The details of the slide 28 are shown in the pending application of Jacob S. Kamborian et al., Serial No. 529,247, filed August 18, 1955, as well as the means for mounting the frame 26 so that it may be tilted. The proximity, that is, the spacing of the feed rolls is controlled by a screw 31 threaded through a boss 32 projecting laterally from the slide 28, the inner end of which bears against the frame 26. By turning the screw the spacing of the rolls may be accurately set and to facilitate such setting shims of known thickness may be employed.

The lasting rolls are driven from a horizontal shaft 25 located in the upper part of the frame 26, which extends rearwardly and has fastened to it a drive pulley 27 which is driven from a pulley 33 located in the base of the machine, which is fast to the drive shaft 35 of a motor M.

The pulling and feeding forces applied to the margin of the material by the rolls 22 and 24 stresses the material substantially perpendicular to the panel and at the same time advances the margin so that successive small areas of the margin are gripped, pulled heightwise and then released as new areas are taken up. As the margin is released it is folded over into engagement with the bottom side of the panel which faces upwardly by a fixed folding device 34 (Fig. 3), which projects forwardly from behind the roll 24 over the edge of the panel parallel to its upper surface. The folding device 34 is retractable however to facilitate introducing the marginal edge between the rolls 22 and 24 and retraction is effected in coincidence with the rolls 22 and 24, that is, as the rolls are separated the folder is retracted and as they are brought together the folder is restored to its operative position. To this end the folder is fastened to a block 36 (Fig. 2), having a dove-tail groove 38 in it which slidably receives the dove-tail 40 of a block 42, the latter being rigidly fastened to the lower part of the frame 26. A pin 44 projects laterally from the block 36 through a slot 46 in the lower end of a lever 48 pivoted on the frame at 50. The upper end of the lever has a slot 52 through which extends a pin 54 projecting laterally from the slide 28. A spring 56 is connected at one end to the pin 54 and at its other end to a rear part of the frame 26 and operates yieldably to hold the slide 28 in a rearwardly displaced position and hence to hold the rolls in engagement. The slide 28 is pushed forwardly to separate the rolls in opposition to the spring 56 by the aforesaid pressure operated cylinder, which is shown diagrammatically in Fig. 8 at 140. Forward movement of the slide at the same time rocks the arm 48 in a counterclockwise direction so that its lower end moves the block 36 rearwardly and hence withdraws the folder 34 to a position back of the roll 24. Operation of the cylinder 140 to release the slide 28 allows it to move rearwardly by reason of the spring and hence to draw the rolls into cooperative relation. The arm 48 at the same time moves in a clockwise direction which advances the folder 34 into its operative position.

As will be clearly seen by reference to Figs. 3, 4 and 6, the marginal edge *m* is held upright with respect to the backing or panel *p*, to which it is being applied, by the roll 24 which has contact with the outer surface of the margin and the roll 22 which has contact with the inner side thereof. The lower end of the roll 22 is rounded off (Figs. 5 and 6) so as to provide an abutment which helps to resist upward displacement of the panel by the heightwise stress applied to the margin. This heightwise movement is also opposed by the overlying portion of the folding device 34 which partially wraps the upwardly projecting margin about the peripheral

surface of the roll 22 and folds the margin downwardly onto the panel.

To assist in moving the panel relative to the pulling over rolls and the folder the work supporting table 20 carries a roller 60 arranged beneath it with a portion of its peripheral edge extending upwardly through a slot 76 in the table below the feed rolls for contact with the panel. The roller 60 is turned in a direction to assist in moving the panel in the direction of feed, as will appear hereinafter. The table 20 is mounted on a rectangular frame 62 (Fig. 1) which is vertically movable between laterally spaced roller bearings 64 carried by a frame 66. The frame 66 is vertically movable on the base 10 and suitable means such as a rack and pinion, the latter being provided with a hand wheel, serves to adjust the heightwise position of the frame 66. Vertical adjustment of the frame 66 permits lowering and raising the table 20 with respect to the operating instrumentalities so that work pieces of different thickness may be covered, such for example as upholstered panels and upholstered articles. The lowering of the table also makes it possible to reach the operating instrumentalities when necessary for repair or adjustment.

The frame 62 is supported on the frame 66 on the upper end of a vertically disposed piston rod 68 which protrudes from the upper end of an air cylinder 70, the lower end of which is fixed in a bracket 72 fastened to the frame 66. When the frame 66 is elevated to bring the table 20 to the desired heightwise position with reference to the pulling over instrumentalities the table is yieldably supported in this position by the air cylinder during the lasting operation so that it will yield to compensate for variations in the thickness of the panel and/or of the covering material.

The roll 60 is of comparatively large diameter, projects upwardly through the table 20 through a slot 76 and is preferably mounted for rotation on a shaft 61 journaled in a bracket fastened to the underside of the table. The shaft 61 is connected by way of suitable means (not shown) to the main drive shaft 25. Optionally the roll 60 may be so mounted that the shaft 61 may be shifted angularly in a horizontal plane, thereby to vary the direction of the feeding force applied to the panel to increase or decrease the latter. Thus, as shown in Figs. 2a and 2b, a turntable 63 is mounted in the table 20 for rotation about a vertical axis. The turntable has the slot 76 in it and the roll 60 is supported from its bottom side. In this case the roll 60 is connected to the main shaft through a universal coupling 81, which permits the wheel to be turned without interfering with its rotation. A handle 78 which may be a forwardly projecting portion of the shaft 61 may be employed to turn the wheel. There is sufficient friction between the turntable and the table to hold it in any given position of adjustment. The adjustment of the feed wheel makes it possible to impart a strong inward feeding force to keep a heavy panel in engagement with the pulling over instrumentalities to insure snug folding and securing of the margin and to lessen the inward feeding force when light panels with thin or beveled edges are to be covered so as to not cause damage thereto.

Next to the folding device 34 in the direction of feed there is mounted the staple mechanism 16 which has a vertically disposed nozzle 80 to which staples are supplied by the stapling mechanism 16 which cuts the staples from continuous lengths of wire and forms them prior to driving, as disclosed in United States Patent No. 2,819,464, dated January 14, 1958. The staples when driven through the margin are crimped within the substance of the panel so that their ends do not project through the covering at the right side.

The construction and operation of the staple driving mechanism need not be related herein except in so far as to say that the stapler is driven from the main shaft 25 and the latch for cocking the staple mechanism at the be-

ginning of the operation is released by an air cylinder, as will appear hereinafter, so as to cause the stapler to drive staples constantly and in timed relation with the feeding of the panel.

The wiper 18 is situated beyond the staple nozzle 80 in the direction of feed and is in the form of a forwardly extending and forwardly tapering roll 84, having on its surface a helically disposed rib 86 for rubbing contact with the marginal edge. The roll 84 is fast to a shaft (not shown) supported in a bearing 87. The shaft 85 has fast to it a pulley 88 over which is entrained a belt 90 driven by a pulley fast to a shaft 94, the latter being driven from the main drive shaft by suitable connections. The bearing 87 is fastened to one end of a lever 96 pivotally mounted on the shaft 94 and the opposite end of the arm 96 is connected to one end of a coil spring 98 which operates yieldably to press the roller 84 downwardly toward the table top 20 and hence against the upper surface of the panel as it is moved therealong. An air cylinder 100 is mounted on the frame and has protruding from it a rod 102 which is connected to the bearing 87 for elevating the bearing and holding it elevated while the machine is at rest, thereby to permit the work to be slid beneath the roll. The wiper roll 84 is rotated in a clockwise direction at a very much higher speed than the feed rolls, approximately 3400 r.p.m., so that the surface of the roll 84 in contact with the work at any given instant has a much higher linear speed than the surfaces of the feed rolls which have contact with the margin at any given instant. Thus the roll 84 tends to pull the marginal edge away from the feed rolls and relative to the panel which is being advanced at the same speed as the marginal edge. The effect of this is to stress the marginal edge in the direction of feed as well as to push it inwardly and thereby to pull that portion of the margin between the roll 84 and the feed rolls taut so that the margin will be snug at the same time the staples are driven. By locating the staple driving head 80 approximately midway between the wiper and the feed rolls and timing the driving of the staples so that the roll 84 has an opportunity to stress the marginal edge between staple driving operations, the margin is constantly shifted in the direction of feed so that there is no chance for it to gradually run off the edge of the panel by a gradual accumulation of slippage in the margin due to the elasticity of the covering material and the natural tendency for it to relax or pull back slightly as it is released by the feed rolls and before it can be secured. Such pull back is not appreciably noticeable in lasting the margin of small panels and shoes and does not detract from the lasting operation as performed by prior machines of this character but for large panels where there are comparatively long runs of straight stapling, the arrangement of the fastening means between the feeding means and the wiping means is highly advantageous and desirable to secure a uniform margin. As a matter of fact the roll operates to push the margin ahead of it, forming very small bulges, as shown in Fig. 7, so that the excess is always taken up but is so distributed as to be unobjectionable. The rubbing action of the wiper roll also helps to press the staples down close to the surface.

The operation of the several instrumentalities is effected by a single treadle which when touched brings the feed rolls together and starts all of the operating instrumentalities, that is, bringing the feed rolls together, advances the folder, raises the table 20, rotates the wheel 60, drives the staples and rotates the wiper. A second touching of the treadle terminates operation of all of the aforesaid instrumentalities so that the machine is restored to its initial position in which the rolls are separated and the table is lowered so that the next piece of work may be placed thereon.

Referring to Figs. 8 and 9, which diagrammatically show the pressure and electrical lines, the sequence of operation which occurs when the foot treadle is tripped for starting and stopping the machine will now be described. In Fig. 9, the foot treadle is indicated at 110. The treadle

is connected to a conventional plug 111 mounted in an outside wall of the base 10, so that it may be disconnected from and plugged in to an outlet from a source of electric power at will. The motor M which drives the main shaft 5 and the motor M¹ which drives the rotary wiper are ordinarily running independently of the foot switch and are switched on and off by switches S and S¹ respectively, both switches being in turn connected through suitable leads to a source of power indicated at 112. In circuit with the switch 110 is a solenoid operated air valve 114 and a microswitch 116 (Figs. 7a and 9). The microswitch has mounted on one side of it a trip 118 which is biased by means of a spring toward the left, as shown in Fig. 7a, so as to permit a contact 120 to have engagement with a contact 122. When the foot switch 110 is closed current is supplied to one side of the solenoid 114. A pivoted arm 124 is mounted on the microswitch housing and has at its distal end a roller 126 which is engaged by movement of the table 20 into operative position to swing the arm 124 counterclockwise, thereby to shift the contact 120 away from the contact 122 and into engagement with the contact 128. Hence when the foot switch 110 is closed again the current is supplied to the opposite end of the solenoid.

Referring to Fig. 8, before the foot switch is tripped air from an external source is supplied through a pipe line 130, pressure regulator 132, and pipe line 134 to the solenoid operated air valve 114, the latter being in an open position. Air under pressure is therefore distributed from the air valve 114 through a bleeder 136 and pipe line 138 to the lower end of a cylinder 140, which has a piston rod 141 projecting therefrom. The rod 142 is connected by way of suitable linkage to the slide 28 to hold the latter in its forward position in opposition to the spring 56 and hence to hold the feed rolls normally separated when the machine is at rest. Air is also distributed under pressure through a pipe line 142 and bleeder 144 to the lower end of a piston valve 146 which blocks a port at its upper end so that air supplied to the valve 146 through the side connection 148 from the line 134 is blocked. Accordingly, there is no air under pressure in the pipe lines 150 and 152 which extend to the table raising cylinder 70. When there is no pressure in the line 152 the table rests at its lowermost position. In the lines 150 and 152 there are a pressure regulator 156, an indicator gauge 158 and two bleeders 157. A pipe line 160 also controlled by the valve 146 is cut off from pressure so that a latch cylinder 162 connected to the staple latch release mechanism occupies a normally retracted position. The latch cylinder when operated disengages the latch controlling the operation of the staple driver. Air is also delivered from the regulator 132 through a pipe line 164 to the upper end of a valve 166 and from the valve 166 through a bleeder 168 and conductor 170 to the lower end of the cylinder 100, which normally holds the rotary wiper in an elevated position and is operative to permit the wiper to be lowered by the spring 98. There is a linkage 174 movable with the piston rod 141 to shift a piston 176 within the valve 166 to cut off the pressure to the line 170 and to deliver it to a line 178, which supplies pressure through a bleeder 180 to a clutch associated with the main drive motor M.

Starting with the machine at rest, the table occupies its lowermost position, the wiper is held in its up position, the feed rolls are separated, the fixed wiper retracted and the stapler inactive. At the lowermost position of the table the arm 124 (Fig. 7a) is held displaced toward the right by a cam 125 fast to the frame so that the contact 120 engages the contact 128. By stepping momentarily on the foot switch 110 the solenoid 114 is shifted to cut off the supply of air through the line 138 to the cylinder 140. The spring 156 accordingly operates to draw the slide rearwardly to close the feed rolls and simultaneously through the lever 48 to advance the

stationary wiper into position. The air in the line 138 is bled out through the bleeder 136. Movement of the piston rod 141 in the cylinder 140 shifts the valve 166 so as to cut off the air pressure through the line 170 to the wiper cylinder 100, thereby allowing the latter to exhaust its air through the bleeder 168 and allowing the spring 98 to lower the wiper. At the same time air under pressure is delivered through the line 178 to the clutch 182 so that the drive for rotating the feed rolls is established. Shifting of the solenoid also cuts off pressure through the pipe line 142, hence allowing the valve 146 to bleed to an open position through the bleeder 144. Shifting of the valve 146 allows air under pressure to enter the valve and the lines 152 and 160. Air entering the line 152 raises the table into operative position and at the same time releases the latch through the line 160 of the cylinder 162. With the table raised into operative position, the wiper lowered into operative position, the rolls engaged and the stapler operating the work is advanced linearly along its edge progressively to fold the marginal edge and staple it.

As the table moves to its operative position the low part of the cam allows the arm to move to the left which allows the contact 120 to move over to the contact 122 so that the next time the foot switch is actuated the solenoid operated valve 114 is shifted to its opposite position, thus restoring pressure to the line 138 and to the line 142 and cutting off the pressure to the lines 152 and 160. The table is therefore lowered and the rolls are separated. Separation of the rolls by advancing the slide restores the valve 166 to its original position which cuts off pressure through the line 178 and allows the latter to bleed through the bleeder 180 to declutch the drive from the main motor to the feed rolls. Cutting off pressure to the staple latch allows the latter to become latched and stay in its latched position so that the staple drive is rendered inoperative.

It should be understood that the present disclosure is for the purpose of illustration only and that this invention includes all modifications and equivalents which fall within the scope of the appended claims.

I claim:

1. Apparatus for pulling the marginal edge of flexible material applied to one side of a rigid panel over the edge of the panel and attaching it to the opposite side, comprising instrumentalities for constantly operating on the marginal edge heightwise to pull successive small areas of the margin heightwise with respect thereto, and to advance the same lengthwise while taking up new areas, a folding device next to the instrumentalities for contact with the edge of the panel to turn the margin down as it leaves the instrumentalities, a support situated below the instrumentalities mounting a work table for yieldably holding the panel engaged with the instrumentalities, panel feeding means on the table operable to assist in moving the panel in unison with the feed imparted to the margin by the instrumentalities, and means mounting the panel feeding means for angular disposition on the table so as to impart a component of feeding force to the panel in a direction to hold its edge against the folding device.

2. Apparatus for pulling the marginal edge of flexible sheet material applied to one side of a rigid panel over the edge of the panel and attaching it to the opposite side, comprising pulling over instrumentalities for progressively stressing the margin heightwise and feeding it lengthwise, a folding blade next to the rolls for turning the margin down as it leaves the rolls, a work supporting table situated beneath the rolls for holding the panel up to the pulling over instrumentalities and panel feeding means on the table operable to assist in moving the panel in unison with the feed imparted to the margin by the pulling over instrumentalities, a turntable supporting the panel feeding means on the work supporting table for angular movement in the plane of the table and means

for turning the turntable without interfering with the operation of the panel feeding means.

3. Apparatus for pulling the marginal edge of flexible sheet material applied to one side of a rigid panel over the edge of the panel and attaching it to the opposite side, comprising pulling over instrumentalities for concurrently stressing the margin and feeding it lengthwise, a folding blade next to the instrumentalities for turning the margin down as it leaves the instrumentalities, a work supporting table situated beneath the instrumentalities for holding the panel up to the instrumentalities, a turntable on the work supporting table flush with the surface, said turntable being turnable about an axis perpendicular to the table and having a slot through it, a roller mounted under the table on the turntable so as to be turnable therewith, a portion of the peripheral edge of the roller extending upwardly through the slot for contact with the underside of the panel, a source of power, a flexible coupling connecting the roll to the source of power to effect rotation thereof, and a handle for turning the table and roll on the support to dispose its plane of rotation at an angle to the direction of feed.

4. Apparatus for pulling the marginal edge of flexible sheet material applied to one side of a rigid panel over the edge of the panel and attaching it to the opposite side, comprising instrumentalities for continuously operating on the margin progressively to pull successive small areas of the margin heightwise and to release them, a support cooperable with the instrumentalities for advancing the panel concomitantly with the movement of the margin as the latter is moved to act upon new areas as the stressed areas are released, a folding member arranged next to the instrumentalities for folding the released margin into contact with the panel, means next to the folder for driving staples into the folded margin, a rotary member having contact with the margin beyond the stapler in the direction of feed and means for effecting rotation thereof so that its surface at any instant of contact with the margin has a greater linear speed than that of the panel.

5. Apparatus for pulling the marginal edge of flexible sheet material applied to one side of a rigid panel over the edge of the panel and attaching it to the opposite side, comprising pulling and feeding instrumentalities operable to stress and feed the margin, means for laying the margin down as it is released by the instrumentalities, other means operative to stress the laid down margin lengthwise and similarly to crowd it inwardly of the edge of the panel, means for driving fasteners into the margin after it leaves the first named means and before it reaches said other means, said other means operating on the driven fasteners to press them flush with the surface of the margin.

6. Apparatus for pulling the marginal edge of flexible sheet material applied to one side of a rigid panel over the edge of the panel and attaching it to the opposite side, comprising instrumentalities operable to stress and feed the margin, means for turning the stressed margin down as it is released by the instrumentalities, fastener inserting means next to the first named means in the direction of feed for driving fasteners into the turned down margin and a rotary wiper operating constantly on the margin beyond the fastener means to advance it at a faster rate than said instrumentalities release the margin.

7. Apparatus for pulling the marginal edge of flexible sheet material applied to one side of a rigid panel over the edge of the panel and attaching it to the opposite side, comprising instrumentalities operable to stress and feed the margin, a fixed folding blade next to the instrumentalities for turning the margin down as it leaves the instrumentalities, a support situated below the instrumentalities for holding the panel up to the instrumentalities and cooperable therewith to advance the work in time with the linear feeding movement imparted to the margin by said instrumentalities, a stapler next to the folder for

inserting staples in the folded margin, a slender rotating roll projecting across the margin and having contact therewith, and means for effecting rotation thereof at such a rate that it shifts the margin ahead lengthwise of the edge of the panel.

8. Apparatus for pulling the marginal edge of flexible sheet material applied to one side of a rigid panel over the edge of the panel and attaching it to the opposite side, comprising fastening instrumentalities for stressing and feeding the margin, a folding blade next to the rolls for turning the margin down as it leaves the instrumentalities, a table mounting a rotatable support situated beneath the rolls for holding the panel up to the instrumentalities, and advancing it at a rate corresponding to the rate at which the margin is advanced by the instrumentalities, a stapler next to the folder, an elongate roll spaced from the stapler by an amount less than the distance between adjacent driven staples and means for rotating the roll at a rate such that the linear speed of its surface at any instant of contact with the margin is greater than the linear speed of the panel.

9. Apparatus for pulling the marginal edge of flexible sheet material applied to one side of a rigid panel over the edge of the panel and attaching it to the opposite side, comprising instrumentalities for constantly operating on the margin progressively to pull successive small areas of the margin heightwise with respect to the panel and to advance the same, a folding device next to the instrumentalities for turning the margin down as it leaves the instrumentalities, a support situated below the instrumentalities and folding device for yieldably supporting the work against the instrumentalities and folding device, said support including means for advancing the work in time with the feeding effect of the instrumentalities on the

margin and means for elevating and lowering the support as the instrumentalities are brought into engagement with the margin and separated therefrom respectively.

- 5 10. Apparatus for operating on work pieces in which there are several instrumentalities movable from inoperative positions to operative positions, said instrumentalities including work gripping rolls, work folding means, a wiper and a work support, fluid operated means for 10 effecting movement of said instrumentalities, to raise the support to bring the work into the sphere of action of the work feeding rolls and to bring them and the folding means into engagement with the work and to effect rotation of the feeding rolls and the wiper, a solenoid operated master valve for controlling the delivery of fluid 15 pressure by way of the master valve to several fluid operated instrumentalities, a manually operable switch and an automatically operable switch wired to be placed in series with the solenoid, said automatically operable switch 20 having contacts shiftable by movement of one of the instrumentalities from one position to another to connect one or the other of the two sides of the solenoid in series with the manually operable switch, said manually operable switch being normally open and when operated, 25 operable to close the circuit to either side of the solenoid.
